WELL PUMPING EQUIPMENT

Benjamin H. Lybyer, 526 W. 10th St., Casper, Wyo.
Filed Jan. 4, 1960, Ser. No. 441

1 Claim. (Cl. 103—203)

This invention relates to oil well pumping equipment, and more particularly to an oil, gas, and sediment separator for use in oil wells, and corresponds generally to the type disclosed in my prior United States Patents 1,698,444, issued July 16, 1925, and 2,345,710, issued April 4, 1944. In particular, the device of the present invention is an improvement over the two above cited prior devices.

It is an object, therefore, of this invention to provide an improved separator for use in an oil well, which separator effectively and simply separates oil, gas, and sediment.

It is another object of this invention to provide an improved separator for use in oil wells, which separator may be readily disassembled for cleaning purposes and may be reused many times.

These and further objects and advantages will become readily apparent to those skilled in the art upon reading the following detailed description taken in conjunction with the appended drawings in which:

FIGURE 1 is a radial sectional view of an oil well casing illustrating the preferred form of separator disposed in working relationship therewith;

FIGURE 2 is a radial sectional view of the preferred form of coupling member shown on an enlarged scale; and

FIGURE 3 is a sectional view taken along line 3—3 of FIGURE 2.

Referring now to the drawings, particularly to FIGURE 1, the preferred form of separator 10 of this invention is shown installed in working relationship within an oil well casing 12. The separator 10 comprises an outer elongated tubing section 14 having a diameter substantially less than that of the well casing. The upper end of an outer section 14 is externally threaded to receive one end 16 of a tubular coupling member 18. The other end of coupling member 18 may be suitably threaded to detachably connect the separator 10 to a working pump barrel 22 extending downwardly within the well casing 12. The lower end of outer tubing section 10 is also exteriorly threaded to receive one end 24 of a tubular coupling member 26. The other end 28 of tubular coupling member 26 is suitably threaded to receive a plug means 30. Plug means 30 preferably comprises a section, or sections, 32 of tubing which may be suitably connected as by the threaded sleeve 34 as desired, to increase the length of the plug means, depending upon the depth of the well. The lower end of the bottommost section 32 is closed off by a bull plug 36 so that the tubing sections 32 and plug 36 define a sediment trap 38. Concentrically arranged within outer tubing section 14 is an inner tubing section 40 having a diameter less than the diameter of the outer tubing section to define a fluid passage 42 therebetween. Inner tubing section 40 is corrugated or pinched at axially spaced positions 44 to provide a plurality of axially spaced interior restrictions 46. Inner tubing section 40 is mounted within outer tubing section 14 by means of the coupling members 18 and 26.

Referring now to FIGURE 2, tubular coupling member 18 is internally threaded at each of its ends 16 and 20 respectively so that the end 20 may threadedly receive pump barrel 22 and the other end 16 may threadedly receive the upper end of outer tubing section 14. Coupling member 18 has an integral thin radial web portion

2

48, which preferably extends diagonally thereacross. Web 48 has a longitudinal bore 50 therethrough and also has a threaded axial bore 52 in communication with the bore 50, defining a T-shaped fluid passage 53. The upper end 5 of inner tubing section 40 is exteriorly threaded to receive one end of a sectional tubular adaptor 54 comprising tubular sections 56 joined together as by a slip fitting. The upper end of the adaptor 54 is exteriorly threaded in order to be threadedly connected to axial bore 52 of coupling 18. The lower tubular coupling member 26 is in all respects similar to upper coupling member 18, and comprises web portion 48 having the through bore 50 and threaded axial bore 52. In assembly, coupling member 26 is in an inverted position relative to the upper coupling 18 so that the lower end of inner tubing section 40 may be threadedly coupled to lower tubular coupling member 26 in its axial bore 52.

An expansible packer 58, which may be made of rubber or may be the conventional neoseal packer, is disposed in surrounding relationship to outer tubing section 14 at a position between its ends and between coupling members 18 and 26. The packer 58 may be secured to the outer tubing section 14 by means of a tubular steel thimble 60, or any other of the well-known means. Outer tubing section 14 has diagonally opposed apertures 62 located adjacent to and above the packer 58 but substantially below coupling member 18.

With the various elements of the separator thus assembled and mounted upon the pump barrel 22, the separator 30 is moved downwardly within the oil well casing 12 until the bore 50 of lower coupling member 26 is disposed beneath the surface of the fluid within the well. The packer 58 being in firm engagement with the walls of well casing 12, provides a fluid-tight seal between the well casing 12 and the separator 10. In operation, then, with the parts assembled as described above and the separator 10 disposed within the well casing, oil, with gas and sediment entrapped therein, enters the separator through the bore 50 in the lower coupling member 26. 40 The oil, gas and sediment may then only follow a path through the T passage 53 and upwardly within inner tubing section 40 towards upper coupling member 16, under well pressure. As the mixed fluid passes upwardly within the tubing 40 it encounters the plurality of spaced 45 restrictions 46 which effect a partial separation of the gas from the oil and sediment. As the mixed fluid continues its upper movement within inner tubing section 40 and adaptor 54, it then passes into the T bore 53 therein and out the bore 50 in the radial web 48 of upper coupling member 18. Gas, which has been liberated from the oil and sediment, passes outwardly from coupling member 18 through the bore 50 and then upwardly within well casing 12 outside of pump barrel 22. The oil with the sediment entrapped, similarly passes outwardly 50 through the bore 50 of upper coupling member 18 and then falls downwardly between well casing 12 and the outside tubing section 14 until it reaches the packer 58; whereupon, the oil and sediment collect and fill the space between well casing 12, packer 58, and separator 55 10. When the pump (not shown) is activated, oil, with the sediment entrapped, enters through the apertures 62 of outer tubing section 14 and into the passageway 42 surrounding inner tubing section 40. Oil is drawn upwardly within the passageway 42 by the negative pressure created 60 by the pump and passes through upper coupling member 18 and around its radial web 48 into the pump barrel 22. The sediment, which falls out of the oil, passes downwardly within the passageway 42 between outer tubing section 14 and inner tubing section 40 and through the 65 lower coupling member 26 and past its radial web 48 into the sediment trap 38. When the sediment trap 38 has become filled such that the sediment begins to back

up within the passageway 42, the pump barrel 22 may be disconnected from the pump, which has been previously shut off, and the separator 10 may be withdrawn from within the well casing 12. Separator 10 may be then disassembled and cleaned and then reassembled and reinserted in the well casing 12 for further use.

It will thus be seen that there has been provided by this invention a device in which the various objects hereinbefore set forth, together with many practical advantages, are successfully achieved. As various possible embodiments may be made of the mechanical features of the above invention, all without departing from the scope thereof, it is to be understood that all matter hereinbefore set forth or shown in the accompanying drawings is to be interpreted as illustrative and not in a limiting sense.

What is claimed is:

A device for separating gas and sediment from oil in a well having a casing and pump barrel disposed therein comprising: an outer tubular member; an inner tubular member concentric within said outer tubular member; said members being of substantially equal length, the inner wall of said outer tubular member and the outer wall of said inner tubular member comprising a fluid passage, said inner tubular member having a plurality of inwardly projecting corrugations defining axially spaced restrictions on the inner surface thereof whereby small entrained gas bubbles are caused to coalesce into larger gas bubbles for subsequent separation from the well fluid; a first tubular coupling having a radial web therein, one end of said coupling secured to said pump barrel,

the other end of said coupling secured to said outer tubular member, said web including a first bore therein in communication with the exterior of said coupling and an axial bore in communication with said first bore and the interior of said inner tubular member; a second tubular coupling having a radial web and secured at one end to said outer tubular member, said web including a first bore in communication with the exterior of said coupling and an axial bore in communication with said first bore and the interior of said inner tubular member, said first bore providing an inlet for the well fluid; plug means secured to the other end of said second coupling; a packer surrounding said outer tubular member and adapted to seal with the well casing to form a sediment trap, and apertures in said outer tubular member spaced above said packer to provide communication between the interior of said outer tubular member and the interior of said casing so that gas free well fluid is allowed to pass to said pump.
